James Hutchison

Design for Oil Cloth
Assigned to Jonathan E. Whipple.

Patented Aug. 5. 1862.

James Hutchison Inventor

J. E. Whipple
R. C. Hancock No. 1,616

Dec. 16/16

James Hutchison, of Lansingburgh, N.Y.
Assignor to
Jonathan E. Whipple, of same place.
Letters Patent No. 1616 dated Aug. 5 - 1862.

The schedule referred to in these Letters Patent and making part of the same,
To all whom it may concern:

Be it known that I, James Hutchison of Lansing-

Dec. 16/16

burgh, in the County of Rensselaer, and State of New York, have invented or produced a new and original design for oil cloths, and I do hereby declare that the following is a full, clear and exact description of the same, reference being had to the accompanying drawings making a part of this specification, said drawings showing one complete octagonal figure of the design and four quarter sections of the adjoining octagons, together with four half sections of the interlying squares.

This design may be described as being formed of outline or skeleton octagons and squares composed of oak stems or bars a, lying on a bed of foliage b, and having upon them at intervals sprigs of flowers c.

Within the central figure A, at its centre there is a group of roses and leaves d.

The figures B, shown in the quarter sections, and having the same contour or outline as the central one, contain at the centre a group of Chinese aster and oak leaves e.

The interlying squares shown in the half sections C, are the same in outline, but the groups within are different: the one being composed of roses f, and the contiguous one of lilies g.

Having thus described my invention, what I claim as new and desire to secure by Letters Patent is,

The general configuration of the within described parts to form a new and original design for Oil Cloths.

Witnesses,

Daniel Flory. }
R. C. Haskell. }

James Hutchison,

Esq.
